By C.C. Shepherd

Attorney

UNITED STATES PATENT OFFICE.

DE WITT H. WYATT, OF COLUMBUS, OHIO, ASSIGNOR TO BURT DRISKELL, OF COLUMBUS, OHIO.

TUB BENCH.

Application filed February 23, 1921. Serial No. 447,092.

To all whom it may concern:

Be it known that DE WITT H. WYATT, a citizen of the United States, residing at Columbus, in the county of Franklin and 5 State of Ohio, has invented certain new and useful Improvements in Tub Benches, of which the following is a specification.

This invention relates to improvements in metallic benches, and has for its primary 10 object to provide a bench which is adapted for use in connection with mechanically operated laundry washing machines for the purpose of supporting tubs in positions contiguous to said machines so that the tubs 15 will be capable at all times of receiving clothes or the like discharged from the wringers of said machines.

In carrying out the invention use is made 20 of a metallic bench which is formed to include a longitudinally extending leg supported frame and to provide in conjunction with said frame a detachable laterally extending extension or supplemental frame, disposed to extend substantially at right angles 25 to the longitudinal frame, the said frame serving, in combination, to produce a bench capable of supporting tubs or the like in a properly distributed manner with respect to a washing machine, particularly 30 machines of the type which include wringers capable of swinging on vertical pivots, in order that by rotating the wringers the clothes may be successively delivered in proper order into each of the tubs.

35 A further object of the invention rests in the construction of a bench of this nature which will include spaced rigidly connected angle irons, upon which the various tubs may be deposited, the irons serving to facilitate shifting of the tubs with but a slight degree of physical exertion, and in this respect the bench serves generally to lighten the labors heretofore involved in retaining tubs or other like receptacles in active use 40 around a washing machine.

45 Other objects of the invention reside in a bench of this character wherein improved structural features obtain, such as the provision of an improved structure for detachably holding the supporting legs of the bench in secured relationship with the longi-

tudinal and transverse frames without involving the use of positive fastening elements, in constructing the leg sockets of the frames in such manner that when the bench 55 is in use the legs will be firmly and securely positioned within the sockets so that a sturdy construction will be presented and one in which teetering and loose connections in the bench will be precluded, and in 60 the provision of simple yet efficient means for detachably connecting the extension frame with the main frame.

A still further object of the invention resides in a bench which will be quick and 65 easy to assemble, of exceptionally staunch construction for its intended purpose and to be capable of being collapsed for transportation or storage purposes so as to assume a very compact condition.

70 With these and other objects in view, as will appear as the description proceeds, the invention accordingly consists in the novel features of construction, combinations of elements and arrangements of parts, hereinafter to be fully described and pointed out in the appended claims.

In the accompanying drawing, forming a part of this specification, and in which similar characters of reference denote like and 80 corresponding parts:

Figure 1 is a perspective view of the improved bench comprising the present invention.

Figure 2 is a vertical transverse sectional view taken on the plane indicated by the line 2—2 of Figure 1.

Figure 3 is a detail longitudinal sectional view taken on the line 3—3 of Figure 1.

Figure 4 is a transverse sectional view 90 taken along the line 4—4 of Figure 3.

Figure 5 is a detail sectional view disclosing the connection between the main and extension frames, and

Figure 6 is a detail sectional view taken 95 along the line 6—6 of Figure 2.

Referring more particularly to the details of the invention, the numeral 1 designates the improved bench comprising the present invention in its entirety. Broadly, this bench consists of a main longitudinally extending frame 2 and a comparatively short, supple-

mental, laterally extending extension frame 3, the latter frame being disclosed to extend to one side and substantially at right angles to the main frame. The said frames 5 include detachable leg sections 4, by means of which the frames are maintained in operative positions but are capable of being collapsed when not actively employed. The bench is formed from suitable lengths of 10 angle irons, which are bent to produce a structure of desired conformation, rigidity and proportion.

The main frame 2 includes a pair of longitudinally extending spaced angle irons 5, which have their ends bent as at 6 to extend downwardly. The opposite ends of the irons 5 are connected by transversely extending angular plates 7, which include side wings 8, and these plates are rigidly secured with 20 the sides 5 by a welding process so that a homogeneously united and substantial construction will result. In combination with the plates 7, the sides 5 may be connected by means of a cross bar 9, also, suitably welded thereto.

To effect the support of the frame 2, the leg sections 4 are employed. These sections preferably consist each thereof of an angle iron member which is bent to produce 30 downwardly diverging legs 10 and an upper horizontally extending cross piece 11. The bending of the angle iron member may be accomplished by removing a portion of the metal at the joints indicated at 12, in 35 order that the desired contour may be given each leg section. The lower portions of the legs 10 are united by cross bars 13 in order to strengthen said sections and to render the same rigid, and the extreme lower ends of said legs are inwardly bent as at 14 to produce supporting surfaces, which are provided with rounded depressions 15, the latter operating to facilitate movement of the bench over the surface upon which it rests.

As previously stated the leg sections are 45 removably connected with the bars 5 without employing positive fastening devices, such as screws or bolts, and this is accomplished by slightly flaring the side walls of the 50 angles 5 and the walls of the plates 7 in a downwardly diverging direction, and sockets 16 are provided, in combination with these walls, by forming the wings 8 of the plate 7 with inwardly directed integral ribs 55 17, shown more particularly in Figure 4. By flaring the walls of the sockets in the manner indicated, the upper ends of the leg sections may be wedged into the sockets so as to be securely maintained therein, without 60 looseness or likelihood of accidental displacement. The construction afforded thereby enables the bench to withstand all ordinary weights which may be placed thereon, and by the inclined walls of the 65 sockets, the addition of weight will merely

serve to more firmly maintain the said leg sections within the sockets. This construction, therefore, eliminates the use of positive fastening elements and enables the bench to be collapsed when not actively employed.

In order to form the bench so that the same will be capable of receiving a clothes basket or an additional tub in close proximity to the wringer of a washing machine, use is 70 made of the extension frame 3 which is capable of being connected with the main frame so as to extend substantially at right angles thereto. The said extension frame includes parallel longitudinally extending bars 18 which terminate in tongues 19 having upwardly directed hooked ends 20. These tongues are adapted to be passed through slots 21 formed in one of the side bars 5, the construction being such that by slightly 75 tilting the extension frame, the tongues 80 may be inserted into the openings 21, and then by dropping the said extension frame so that the same will be normally positioned, the hooked ends 20 will engage with the inner edge of the cooperative bar 5 to prevent 85 undue movement on the part of the extension frame. The outer end of the extension frame is equipped with a removable leg section 22, which is adapted to be received within sockets which correspond in construction to those provided for the leg sections of the main frame, formed in the outer 90 ends of the extension frame.

In view of the foregoing description, taken in conjunction with the accompanying drawing, it will be apparent that the present invention provides a bench which will be practical and useful for many different purposes, its use in connection with mechanically operated washing machines being merely one of many to which the bench may be placed. The construction has the advantage of being light in weight, collapsible and yet capable of being substantial and rigid when set up for service. Rivets and 100 like fastening devices have been eliminated and also sharp projections which may have a tendency to rend or to tear clothing.

What is claimed is:

1. A metallic bench comprising an elongated frame, a laterally extending supplemental frame disposed to extend at right angles to said main frame, said supplemental frame being formed to include a pair of parallel bars, tongues provided on the ends of said bars and arranged to be received within paired spaced slots provided in said main frame, upturned projections being provided upon the ends of said tongues for engagement with the inner edge of one of 115 the bars of the main frame, and serving to engage either pair of slots to lock said supplemental frame in connection with the main frame, and leg sections carried by 120 said frames.

2. In a metallic wash tub bench, a frame including a pair of spaced parallel bars, a transversely extending cross rail uniting the ends of said bars, said rail being formed to include downwardly sloping side walls and integral side wings, one of said wings being provided with a substantially vertically extending rib, the said rib in conjunction with the side walls of said rail serving to define a substantially wedge shaped socket, and a removable leg section arranged to occupy said socket.
- 5 In testimony whereof I affix my signature.

DE WITT H. WYATT.
